Primary Examiner — Cynthia Ramirez*Assistant Examiner* — Michael Maharajh(74) *Attorney, Agent, or Firm* — Kirk A. Buhler; Buhler & Associates(57) **CLAIM**

The ornamental design for a one-way valve cap, as shown and described.

DESCRIPTION

FIG. 1 is an exploded top perspective view for a one-way valve cap showing my new design;

FIG. 2 is an exploded underside perspective view thereof;

FIG. 3 is an exploded front side view, the rear side view being the same image thereof;

FIG. 4 is an exploded right side view, the left side view being the same image thereof;

FIG. 5 is a top side view thereof;

FIG. 6 is a bottom side view thereof;

FIG. 7 is a front side sectional view taken along lines 7-7 from FIG. 4 thereof;

FIG. 8 is a right side sectional view taken along lines 8-8 from FIG. 3 thereof;

FIG. 9 is a sectional view taken along lines 9-9 from FIG. 4 thereof;

FIG. 10 is a sectional view taken along lines 10-10 from FIG. 4 thereof;

FIG. 11 is a sectional view taken along lines 11-11 from FIG. 4 thereof;

FIG. 12 is a sectional view taken along lines 12-12 from FIG. 4 thereof;

FIG. 13 is a front side view thereof; and,

FIG. 14 is a sectional view taken along lines 14-14 from FIG. 13 thereof.
